US00D577018S

(12) **United States Design Patent**
Lin

(10) **Patent No.:** US D577,018 S
(45) **Date of Patent:** ** Sep. 16, 2008

(54) **MOBILE COMMUNICATION DEVICE**

(75) Inventor: **Yen Hung Lin**, Taoyuan (TW)

(73) Assignee: **High Tech Computer Corp.**, Taoyuan, Taoyuan County (TW)

(**) Term: **14 Years**

(21) Appl. No.: **29/296,915**

(22) Filed: **Oct. 31, 2007**

(51) **LOC (8) Cl.** 14-02

(52) **U.S. Cl.** D14/346; D14/345; D14/138

CLAIM

The ornamental design for a mobile communication device, as shown and described.

DESCRIPTION

FIG. 1 is a perspective view of a mobile communication device showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
